UNITED STATES PATENT OFFICE.

INA CLORUS COIN, OF DENVER, COLORADO.

DESIGN FOR A SPRAYER.

SPECIFICATION forming part of Design No. 35,168, dated October 8, 1901.

Application filed August 28, 1901. Serial No. 73,630. Term of patent 7 years.

To all whom it may concern:

Be it known that I, INA CLORUS COIN, a citizen of the United States, residing at Denver, (Alcott P. O.,) in the county of Arapahoe and State of Colorado, have invented and produced a new and original Design for a Sprayer, of which the following is a specification.

This invention relates to a new and original design for a sprayer, and the essential features reside in the design as illustrated in the accompanying drawings, wherein—

Figure 1 is a perspective view of a sprayer embodying the features of the design. Fig. 2 is a longitudinal vertical section of the same.

The design is characterized by a body 1 of elongated form and having depending side members 2, which converge toward the front end of the device to give the latter when sup-

ported a downward inclination toward the front. At the front end of the body is an up-standing forwardly-inclined terminal portion 3, having the opposite sides bent rearwardly at an angle, as at 4, and also provided with intermediate corrugations 5. On the rear upper portion of the body is a U-shaped element 6, formed with terminal flanges 7.

Having thus described the invention, what is claimed as new is—

The design for a sprayer, as herein shown and described.

In testimony that I claim the foregoing as my own I have hereto affixed my signature in the presence of two witnesses.

INA CLORUS COIN.
